UNITED STATES PATENT OFFICE.

ALLEN C. STALEY, OF LA FAYETTE, INDIANA.

CONTROL SYSTEM FOR LIQUID-FUEL BURNERS.

Application filed December 7, 1921. Serial No. 520,630.

The object of my invention pertains to a system to automatically control the combustion of liquid hydrocarbon fuel, so as to maintain predetermined conditions of temperature and pressure or both in a steam boiler or generator.

In the drawings, I illustrate various improved structures which embody my invention, also the piping, wiring, etc., in operative relation to the various units connected therewith.

Other objects of my invention will appear hereinafter.

Referring to the accompanying drawings, which are made a part hereof and on which similar reference characters indicate similar parts,

Figure 1 is a diagrammatic sketch of the control system embodying my invention the various mechanisms involved being shown in their operative relationship, and

Figure 2 is a vertical section of the blower, burner, pressure control device, combustion chamber, and steam generator shown in operative relation.

The system shown is particularly adaptable to use in steam driven automotive apparatus but not necessarily limited to this application.

This class of service demands exceedingly simple and sturdily reliable mechanism, capable of operation by mechanically unskilled operators, and this, as well as other objects hereinafter pointed out are attained in this system.

Referring to Figure 1, reference numeral 10 is an electric dynamo of a capacity usually found on internal combustion engined automobiles, having for illustration, a charging rate of 10 to 15 amperes at 6 volts, at average car speeds. Reference character 11 represents a reverse current relay of usual design, to prevent discharge of battery through the dynamo, when the car is stationary, or the voltage generated by the dynamo is less than that of the battery. A 6-volt storage battery 12 is provided of any desired capacity, such as 80 to 100 ampere hours, which is ample to handle the system. A starting switch 13 operates starting motor 14 which is provided with an engaging clutch 15 so as to drive air blower or fan 16, fuel pump 17, and small steam engine or turbine 18 which are all connected permanently so as to rotate together as one

unit. When the starting switch 13 is opened, stopping the motor, the clutch 15 automatically disengages and when steam is up the blower, pump, etc., are driven from the small steam engine 18.

A steam generator represented as 19 is provided and a steam line 20 leads therefrom to supply steam to the engine 18, the steamlime 20 having in its length a hand valve 21 for shutting off the supply of steam to the engine 18. A vibrating spark coil 22 is of ordinary construction for producing a spark sufficient to ignite primary or nozzle burner 23. The spark producing means is so arranged as to be operative only when starter switch 13 is closed, as it receives its supply of current from the same circuit operating the motor 14. If a spark coil is used, the secondary winding is connected to a spark plug 24 shown diagrammatically in Figure 1 and in greater detail in Figure 2. The spark plug 24 is so located as to ignite the spray of finely atomized fuel emitted from nozzle 23. The main nozzle or burner 25 receives its fuel from a source of supply represented by tank 26 through feed piping 27. A float chamber or other suitable means 28 is adapted to control the fuel level at nozzle 25, if this is of the aspirating type as described.

Fuel pump 17 which supplies the primary nozzle 23 is shown receiving fuel from the same supply tank as the secondary nozzle 25 but in case different fuels are used, separate tanks or other sources of supply may be furnished for each nozzle.

In starting up the plant when it is cold, the mode of operation is as follows: Starting switch 13 is closed energizing motor 14 which is caused to rotate rapidly, operating through engaging clutch 15, the blower 16, the fuel pump 17, and the steam engine 18. The spark coil 22 is at the same time energized to produce a spark at the plug 24. The pump 17 is operated to force fuel to nozzle 23 and the blast of air from the fan 16 creates a flow of fuel from aspirator nozzle 25. The fan 16 and nozzles 23 and 25 are arranged within a suitable casing 29 as best shown in Figure 2. Air is forced from the fan into passages 30 and 31, the passage 31 having an orifice 32 to restrict the supply of air to the nozzle 23, while the passage 30 is provided with a valve 33 which will later be described in detail. This valve

regulates the flow of air from the fan 16 to the nozzle 25. The sparking of the plug 24 will start the combustion at nozzle 23 and spread thence to the nozzle 25, the combined combustion of the fuel from both nozzles extending through the common passage 34 and into the main combustion chamber 35 of the generator 19.

Owing to the special design of the steam 10 generator sufficient pressure is raised in less than one minute to operate blower pump etc., from the steam engine 18. Starter switch 13 is then opened causing spark coil and motor 14 to cease to function and clutch 15 15 is disengaged.

In systems heretofore used on steam automobiles, the electric motor continues to function at all times that the fire is in operation, requiring large and expensive 20 motor, dynamo, and storage battery. By means of this system much smaller and less costly units are required, the starting motor using but 30 to 40 amperes for a comparatively short period. Steam having been 25 raised the system is entirely independent of the electrical system, an extremely valuable characteristic of my invention.

Also, in case of failure of the electrical 30 system the blower may be provided with a hand crank for cold starting and the burner thus ignited by other than electrical means, which gives the user of this system a confidence not heretofore secured by use of the electrical control exclusively.

35 The first phase of starting the fire and raising the steam having been secured, as explained above, the second phase of operation, entirely automatic, and independent of the operator's attention, is disclosed in the 40 following:

Referring to Figure 2, piston housing 35 is secured adjacent the casing 29. Within the housing 35 is a piston or diaphragm 36 forced downwardly by spring 37. The 45 under face of the piston is exposed to the pressure of the steam from the generator which is introduced through pipe 38. The piston or diaphragm is so arranged that at any predetermined pressure in the boiler 50 or steam generator, the pressure therein is communicated through pipe 38 to the piston 36 whose motion is opposed by spring 37, capable of adjustment to any required range or scale of operation.

55 As the pressure gradually approaches this predetermined point or condition, the movement of the piston or diaphragm against the spring, actuates a shutter or damper valve 33, by means of the connecting linkage 60 39, 40 and 41 causing a reduction in the flow of air past the burner nozzle 25 which if of the aspirating type as shown reduces the fuel in like proportion so as to maintain at all times a completely combustible mixture 65 of fuel and air.

While the drawing shows a secondary nozzle of the aspirating type, this may be of the pressure atomizing type receiving its fuel from the same fuel source, if desired, as the primary nozzle 23, and furnished with 70 a needle valve or other means for varying the delivery of fuel in definite relationship to the volume of air passing the shutter 33.

When the predetermined high pressure, as mentioned above, is reached, the flow of fuel 75 from nozzle 25, is practically stopped, the shutter 33 being in a closed position and stopping the flow of air from fan 16 past the nozzle 25.

The pilot or primary nozzle 23 continues, 80 however, in operation and is of relatively small capacity as compared with that of the intermittently operating and graduated burner nozzle 25, the fuel from the primary nozzle being of sufficient amount to maintain 85 the steam in the generator at a working pressure with the car stopped, supplying the necessary heat to overcome the radiation and other losses from the steam generating plant and connecting piping, as well as, to supply 90 the steam to the engine 18 to operate the lower or fan engine.

As the demand for steam increases due to the operation of the main engine of the car, or other cause, the pressure in the steam 95 generator falls, and the steam piston is reversed in its motion by the action of the resisting spring, opening the shutter and causing fuel to flow from the secondary nozzle. When any predetermined required pressure 100 is secured as determined by the adjustment of the spring 37 and connecting linkage the shutter 33 is wide open and the burner is operating at its maximum capacity and generating the maximum quota of steam. 105

It is to be particularly noted that this system does not operate on the well known "cut in and cut out" principle, as used in many designs, but a graduated fire is furnished at all times in proportion to the demand for steam with the following desirable 110 results.

It is a well known fact that when steam generating, superheating, and other surfaces, such as combustion chamber linings, etc., are subjected to sudden temperature changes as caused by the cut in and cut out method of fire control, deterioration is much more rapid than when the change is a gradual one.

Again, it is quite difficult to prevent a certain amount of noise from accompanying the usual combustion of fuel, particularly, when this is intermittent in its operation and on full blast, when in operation. It is particularly noticeable, as it is of an intermittent nature, and is quite different from the steady tone of the more common and better understood internal combustion engine vehicles. 125

Also, as in average operation, the steam 130

plant is called upon for less than its full capacity, the fire operates at a correspondingly reduced rate and deterioration of boiler, superheater, and other surfaces subjected

5 to the heat of combustion are more than correspondingly reduced by the comparatively moderate heat to which they are subjected the greater portion of the time, as in the cut in and cut out system of combustion where the intensity of combustion is always a maximum whatever the load, the steam generation being controlled by the time between or duration of firing periods only.

Furthermore, when superheating coils are 15 used with the cut in and cut out method of operation, there is a decided tendency to secure a wide variation in steam temperature with a consequent more rapid deterioration of coil surface, engine, and valves, as well as

20 difficulties in lubrication.

It is desired to call attention to the fact that the pilot light or primary burner 23 does not necessarily serve as an ignition jet, nor is this a rich mixture process of combustion as is used in certain other systems which have been developed. The operation of the burner is more fully described in a co-pending application, Serial No. 540,551, filed March 2, 1922, and it is to be noted 25 that this primary burner is in continuous operation at all times when the plant is in service.

The secondary burner or nozzle is also in continuous operation at all times that the 30 main engine is in operation, although never fully open except when the plant is loaded to its maximum capacity. In other words the system is composed of two general parts, a primary constant capacity unit of such a 35 size as to handle minimum plant requirements only, and a secondary unit or units which adjust their capacity automatically to handle the increase in load over and above the minimum requirement only.

40 When stopping the car or plant for any cause the primary burner may or may not be left in operation as desired. In cold or freezing weather, leaving this burner on would have the desirable effect of keeping 45 the system warm and steam up ready for a quick start. In milder weather, and owing to the quick initial start possible with properly designed steam generators, it is better practice to shut off the fire entirely.

50 This is readily accomplished by closing the hand valve 21, Fig. 1, which stops the flow of steam to the blower engine, stopping the fuel pump and consequently all combustion.

55 In starting again with pressure still up in the steam generator, this valve is opened at the same time that the starter switch 13 is pressed and the fan and pump are immediately brought up to speed and the fire lighted by the spark in the usual manner.

60 By making the steam engine so as to be non-

starting except when cranked by the motor there is no danger of the fuel being delivered to the combustion without at the same time putting on the spark for ignition. This is readily accomplished by suitable design of 70 the fan engine valves.

A summary of the outstanding features of the system as described, is as follows:

1. Extreme simplicity and sturdiness of 75 all parts.

2. Freedom from spark delay devices, differential pressure control for cut in and cut out systems of firing, air tanks, air compressors, and the like.

3. Simple and inexpensive electrical 80 equipment standardized in other industries, and not necessary to the successful operation of the system, in case of failure to function properly.

4. Fire of such a character as to be practically noiseless graduated to the load, resulting in long life of the associated parts and securing high efficiency of the steam generating plant.

5. Constant steam temperature and pressure 85 at any particular load or set of operating conditions.

It will be evident to those skilled in the art that numerous modifications can be made in my advice without departing from 90 the spirit of the invention and therefore I do not limit myself to the specific embodiment of the invention shown in the drawings and described in the specification but only as indicated in the appended claims.

Having thus fully described my said invention, what I claim as new and desire to secure by Letters Patent, is:

1. A control system for liquid fuel vapor pressure generators comprising a primary 105 fuel nozzle, a secondary aspirator fuel nozzle, a pump for supplying fuel under pressure to the primary nozzle, a float controlled chamber for controlling the supply of fuel to the secondary nozzle, means for supplying air to both nozzles, means for diminishing the air supply to the aspirator nozzle as the vapor pressure increases beyond a predetermined point, and an auxiliary prime mover operated by the vapor, said auxiliary 110 prime mover being arranged to operate the fuel pump and air supplying means at times when the secondary nozzle is inoperative, substantially as set forth.

2. In a steam driven vehicle, a steam generator, a burner therefor including a liquid fuel nozzle, a pump for supplying fuel to the nozzle, an air blower for supplying air to said burner, an auxiliary steam driven prime mover having driving connection with the air blower and the fuel pump, an electric starting motor detachably connected with said air blower and fuel pump, means for producing an electric spark adjacent said nozzle, means for simultaneously causing the 120

electric motor to operate said fuel pump and the air blower to generate an initial steam pressure, and means for causing the auxiliary prime mover to operate the air blower and the fuel pump to maintain steam pressure at all times including times when the vehicle is at rest, substantially as set forth.

3. A liquid fuel burner comprising a casing having a chamber at the upper end, a fan in the chamber, a passage at one side of the casing extending downward from the chamber intersecting the first passage, a primary burner in the second passage, a secondary burner in the first passage adjacent the junction of the two, a spark plug immediately below the primary burner, a partition above the primary burner having a perforation of limited extent immediately above the nozzle of said burner, and a valve 20 in the first-named passage for adjustment

of the air current therein, substantially as set forth.

4. A liquid fuel burner comprising a casing having a chamber at the upper end, a fan in the chamber, a passage at one side 25 of the casing extending downward from the chamber intersecting the first passage, a pressure-operated primary burner in the second passage, a suction-operated secondary burner in the first passage adjacent the junction of the two, a spark plug immediately 30 below the primary burner, a partition above the primary burner having a perforation of limited extent immediately above the nozzle of said burner, and a valve in the first-named passage for adjustment of the air current therein, substantially as set forth.

In testimony whereof I affix my signature.
ALLEN C. STALEY.
